UNITED STATES PATENT OFFICE.

CHARLES FREBORG, OF KANKAKEE, ILLINOIS, ASSIGNOR TO PRICE & TEEPLE PIANO COMPANY, OF CHICAGO, ILLINOIS, A CORPORATION OF ILLINOIS.

GOVERNOR FOR PLAYER-PIANOS.

1,381,911.

Specification of Letters Patent. Patented June 21, 1921.

Application filed July 31, 1919. Serial No. 314,524.

To all whom it may concern:

Be it known that I, CHARLES FREBORG, a citizen of the United States, residing at Kankakee, in the county of Kankakee and 5 State of Illinois, have invented certain new and useful Improvements in Governors for Player-Pianos, of which the following is a specification.

This invention relates to improvements in 10 governors for player pianos, and has for its object to provide an improved form of construction in which a governor is provided to control the exhaust of air automatically from a player piano motor.

15 Another object of the invention is to provide a construction comprising an exhaust or vacuum motor and a governor, located adjacent the one to the other, in order to cut down the distance which the exhaust air 20 has to travel between the motor and governor, thereby providing quicker action of the governor upon the motor.

Still another object of the invention consists in the peculiar construction of the 25 governor mechanism.

These and other objects of the invention will be more fully set forth and described in the following specification and shown in the accompanying drawings, in which—

30 Figure 1 is a front elevation of a portion of the player piano construction, part of the governor member being shown in section, and the cover thereof being shown as removed;

35 Fig. 2 is a vertical section through the governor member; and

Fig. 3 is a vertical section through the 40 motor member.

Like numerals refer to like elements 45 throughout the drawings, in which—

10 designates generally a vacuum motor comprising a plurality of double bellows 11. The motor is provided with a fixed frame or wall 10^a—see Fig. 3—which is tapered 45 or inclined from top and bottom toward the central or pivotal point 10^b. Each of the double bellows is formed by the pivoted wall 11^a, which is attached to the wall or frame 10^a by means of the inner end pieces 11^b, collapsible side walls 11^c, and collapsible end wall 11^d. This construction provides a pair 50 of bellows A, B, for each double bellows 11, the bellows B of each series being collapsed when the bellows A is expanded, as will be

obvious. This construction, however, forms 55 no part of my present invention, and need not be further specifically described, save to state that the exhaust duct 12 extends transversely through the fixed wall frame 10^a, and a port 12^a leads therefrom to the 60 upper surface of the wall 10^a for each of the double bellows. Auxiliary ducts 12^b lead from the interior of each of the bellows A and B to the surface of the wall 10^a, and a slide valve 14, having a groove 14^a on its 65 under surface, is provided, one for each double bellows 11.

Assuming the exhaust duct 12 to be in communication with the air-exhausting means, or region of vacuum, when the slide 70 valve is in the position shown air will have been exhausted through the lower duct 12^b, groove 14^a, port 12^a into the exhaust duct, resulting in the collapsing of the bellows B. At the same time the duct 12^b furnishes 75 communication between the atmosphere and bellows A, which permits its expansion. A connecting rod 15 connects each of the slide valves 14 to a rocker arm 16, which is also pivotally attached at its other extremity to 80 a finger 17 secured to the lower portion of the wall 11^a. The rocker arm is also pivotally mounted upon a crank shaft 18. The bellows are so arranged and timed as to rotate the crank shaft—see Fig. 1,—such rotation automatically operating the slide valves, 85 as will be obvious. The rotation of the crank shaft 18 is transmitted to the pinion 18^a, and suitable gearing is provided to rotate the winding roll or music roll, as desired. 90

Located adjacent one end of the motor 10 is the governor member, generally indicated by the numeral 20—see Fig. 1. This governor member is secured by screws 20^a to one 95 end of the wall or frame 10^a, a spacing strip 20^b being interposed. An aperture 21 is provided in the adjacent side of the governor frame 22, and into this aperture projects and closely fits the tube 12, as shown 100 in Fig. 1.

The governor, as stated, comprises the fixed frame 22 and the transverse piece 23 extending between the sides thereof and near the bottom, as shown in Figs. 1 and 2. 105 This partition forms with the frame the governor chamber C and the auxiliary chamber D. A duct 22^a is provided in one side

wall of the frame, and extends from the aperture 21 to and into the chamber D.

A main exhaust duct 25 is provided in the supporting bar 26, and leads to any suitable form of exhausting means. From this main exhaust duct leads the duct 27 upwardly through a portion of one side of the frame 22 and across the partition 23,—as shown in Fig. 1—from whence it communicates with the chamber C through the duct 28—see Fig. 2.

Pivottally attached by a flexible strip at 30 is the movable bellows wall 31,—see Fig. 2—which has the usual flexible end and side walls 32, 33, respectively. Projecting inwardly from the movable wall is the bridge member 31^a slotted at the top, as indicated by numeral 31^b—see Fig. 1. A cross pin 31^c extends across the slot 31^b, as shown in Fig. 2. A rod 37 extends across the governor chamber C, and a bell crank 38 is looped about said rod at 38^a. The end 38^b of the bell crank rests upon the pin 31^c, and at its other end is angularly directed and apertured at 38^a to engage the end 40^a of a spring 40. The other end of this coil spring engages an aperture 41^a of the threaded rod 41, projects upwardly through the top of frame 22, and is engaged by the threaded knurled nut 42. It will be obvious that the rotation of this nut will operate, through the rod 41, to vary the tension in the spring 40, and thereby through the medium of bell crank 38 to resist the collapsing of the bellows, of which 31 is the movable wall.

A slide valve 43 slides upon the inner face of the partition 23 to control the flow of air through the passage 28. This slide valve is operably attached to the movable wall 31 by means of the wire member 44, which is of sufficient resilience to maintain the slide valve 43 closely pressed against the partition 23. It will be apparent that the movement of the wall 31 will result in like movement of the slide valve 43, so that when the bellows formed by the movable wall are collapsed the passage 28 will be substantially closed by the slide valve 43.

The auxiliary chamber D is divided into two portions by the plate 45, which is suitably apertured, as indicated by numeral 45^a—see Fig. 1—to provide communication between the two portions of the chamber D. A rotatable disk valve 46 is carried by the rotatable shaft 47 extending through the cover 48 of the governor 20. This disk is maintained in close contact with the plate 45 by means of the spring 49, coiled around the shaft 47, which latter also carries outwardly of the governor a lever 47^a which is attached to an operating rod 49, or the like. The disk valve 46 is apertured, as indicated at 46^a, and coacts with the peculiarly shaped aperture 45^a from the chamber D to the governor chamber C, thereby controlling the

tempo, as is well known to those skilled in the art, by controlling the flow of air from the motor. The valve 46 is known as the tempo valve.

In the operation of my device it will be apparent that assuming a vacuum to obtain in the main duct 45, by operation of exhausting means—not shown—flow of air will ensue from the double bellows 11 of the motor 10, through the duct 12, passage 22^a, 75 and into the chamber D, in which, the tempo valve being in open position, air will flow through aperture 45^a into the bellows formed by the movable wall 31, and into the chamber C, from whence it will flow through 80 the passage 28 into the duct 27, and from there into the main duct 25.

Assuming the pressure to be constant, the amount of air flowing will be regulated by the size of the aperture 45^a, and the speed 85 of the motor will be substantially constant. As is well known, however, fluctuations in the vacuum or partial vacuum, caused by the exhausting means, frequently occur, and it is the purpose of the governor to combat 90 these fluctuations. Assuming a sudden increase in the vacuum, *i. e.*, a reduction of pressure, this vacuum will be transmitted through governor chamber C from the main exhaust duct 25. This reduced pressure 95 will operate to collapse, or partially collapse, the governor bellows against the action of coil spring 40. This results in a partial closing of the passage 28 by the slide valve 43. This reduction of the passage, 100 coupled with the increased vacuum, maintains the flow of air as it was before fluctuation, assuming that the tension of the spring 40 is properly adjusted. In short, when the vacuum is increased the flow of air 105 which determines the speed of the motor is maintained constant by reducing the size of the passage 28.

The governor 20, being attached and located adjacent the motor, results in the provision of a comparatively short flow between the bellows 11 and the governor chamber, so that the compensating action of the governor is immediately felt by the motor, in contradistinction to devices hitherto used, which were located at some distance from the motor, and which allowed perceptible periods of time to elapse before compensation of the governor was effective at the motor, thereby impairing the value of 115 the governor.

It will be obvious that my construction is susceptible of modification and improvement, and I do not therefore wish to be restricted to the form shown and described, 125 except as defined in the appended claims.

What I claim is:

1. A governor for vacuum motors comprising a bellows member having a movable wall, and means to resist the collapsing of 130

said bellows, said means comprising a pivoted bell crank, one end of said bell crank being attached to a spring member.

2. A governor for vacuum motors comprising a bellows member having a movable wall, means to resist the collapsing of said bellows, said means comprising a pivoted bell crank, one end of said bell crank being attached to a spring member, and means to 10 adjust the tension of said spring.

3. A governor for vacuum motors comprising a bellows member having a movable wall, and means to resist the collapsing of said bellows, said means comprising a pivoted bell crank, said movable wall having a bridge member, one end of said bell crank being in contact therewith.

4. A governor for vacuum motors comprising a bellows member having a movable

wall, and means to resist the collapsing of 20 said bellows, said means comprising a pivoted bell crank, said wall having a bridge member, and a pin carried by said bridge member, one end of said bell crank being in contact with said pin.

5. A governor for vacuum motors comprising a bellows member having a movable wall, and means to resist the collapsing of 30 said bellows, said means comprising a pivoted bell crank, one end of said bell crank being attached to a spring member, said movable wall having a bridge member, one end of said bell crank being in contact therewith.

25
In testimony whereof I have subscribed 35
my name.

CHARLES FREBORG.
